UNITED STATES PATENT OFFICE.

FRANK VAN DUYNE, OF ST. PAUL, MINNESOTA.

REFRIGERATOR SHOW-CASE.

1,023,975.

Specification of Letters Patent.

Patented Apr. 23, 1912.

Application filed October 12, 1910. Serial No. 586,665.

To all whom it may concern:

Be it known that I, FRANK VAN DUYNE, a citizen of the United States, residing at St. Paul, in the county of Ramsey and State of Minnesota, have invented certain new and useful Improvements in Refrigerator Show-Cases, of which the following is a specification.

My invention relates to improvements in refrigerators as embodied particularly in a refrigerator show case, its object being to secure the maximum amount of circulation, simplicity and cleanliness, and to this end consists in the features of construction and combination hereinafter particularly described and claimed.

In the accompanying drawings forming part of this specification, Figure 1 is a longitudinal vertical section of my improved refrigerator show case; Fig. 2 is a perspective view of the grating; Fig. 3 is a detail of a shelf bracket; Fig. 4 is a section on line *iv—v* of Fig. 1; Fig. 5 is a perspective view broken away of one of the refrigerator partition walls; and Fig. 6 is a section on line *y—y* of Fig. 4.

Referring to the drawings 2 represents the bottom, 3 the ends, 4 the front, 5 the back, and 6 the top of the show case. The back 5 is provided with a plurality of suitable doors 6. In each end of the show case is arranged a plurality of shelves 7, said shelves being supported by suitable brackets 8. The brackets 8, as shown, are vertically adjustable through the medium of pins 9 projecting rearwardly therefrom and adapted to extend into key holes 10 in the uprights 11 secured upon the inner walls of the show case. Arranged adjacent to the inner ends of each set of shelves 7 is a vertically disposed sheet 12 of suitable material as opalescent glass, immediately outside of which is positioned a frame 13 formed with an outer covering of horizontally corrugated metal 14. The partition wall frame 13 is secured to the uprights 11 upon the back of the case as by means of screws 16 fitted into slots 26 whereby to allow easy removal of said frame. The glass sheet 12 is held in position at its lower end by means of turn buttons 17 and at its upper end by being positioned between the top bar of the frame and pins 18 projecting inwardly from the upright 11. Supported below the plate 12 and spaced therefrom is a horizontal inwardly extending plate 19. The top cross

bar 20 of the partition wall 13 is formed with a plurality of openings 21, said partition wall and plate 12 being spaced from the top of the case. The space between the opposite partition walls 13 forms the ice chamber. Arranged in the bottom of the ice chamber is a grating 22 and underneath the same are the downwardly directed deflecting walls 23. The show case is provided underneath the grating with a suitable drainage pipe 24. Supported by the show case above the ice chamber is a suitable heat insulating wall 25.

In operation, with the ice chamber filled with ice the cold air will pass downwardly being deflected by the deflector walls 23 underneath the plates 19 passing around said plates upwardly through the food chambers. A secondary circulation of air takes place through the openings 21 and underneath the lower end of the plate 12 and upward through the inner portion of the food chamber. The main circulation of air passing upwardly around the plates 19 will mainly affect the outer portions of the food chamber, while the secondary circulation of air will mainly affect the inner portions, thus causing a complete and effective cold air circulation through the food chamber.

I claim as my invention:

1. In a show case refrigerator of the class described, the combination with a case, of vertical spaced partition walls arranged therein forming an intermediate ice chamber, a food chamber adjacent one of said partition walls, said partition wall being formed with spaced walls, the space between the walls of said partition communicating at its upper end with said ice chamber, said ice chamber communicating below said partition wall direct with the food chamber, and means for deflecting the air from the space between the spaced walls of the partition into the bottom of the food chamber independently of the air passing from the ice chamber to the food chamber.

2. In a show case refrigerator of the class described, the combination with a case, of vertical partition walls spaced from the ends of the case to form food chambers and spaced from each other to form an intermediate ice chamber, each of said partition walls being formed with spaced walls, said partition walls being spaced from the bottom of the case to form a passage from the

ice chamber to the food chamber and a horizontal wall extending outwardly from the lower end of each partition wall into the food chamber, said horizontal walls closing the spaces between the lower end of the spaced walls of the partitions whereby the air is directed from the spaces between said walls into the food chamber independently of the air passing directly from the ice 10 chamber to the food chamber.

3. In a show case refrigerator of the class described, the combination with a case, of vertical partition walls spaced from the ends of the case to form food chambers and spaced from each other to form an intermediate ice chamber, each of said partition walls being formed with spaced walls, said partition walls being spaced from the bottom of the case to form a passage from the 20 ice chamber to the food chamber, a horizontal wall extending outwardly from the lower end of each partition wall into the food chamber, said horizontal walls closing the spaces between the lower end of the 25 spaced walls of the partitions whereby the

air is directed from the spaces between said walls into the food chambers independently of the air passing directly from the ice chamber to the food chambers, a grating between said partition walls, and deflector 30 plates below said grating.

4. In a show case refrigerator, the combination with a case, of vertical partition walls spaced from the opposite ends thereof to form food chambers and spaced to form 35 an intermediate ice chamber, a plate removably supported upon the inner side of each partition wall and spaced therefrom, the space between said plate and wall communicating at its upper end with the ice chamber and at its lower end with the food chamber, and a horizontal wall extending outwardly from each partition wall and spaced from said removably supported wall. 40

In testimony whereof I affix my signature 45 in presence of two witnesses.

FRANK VAN DUYNE.
